UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A DRESS.

Application filed February 10, 1925. Serial No. 12,328. Term of patent 3½ years.

To all whom it may concern:

Be it known that I, TAUBE DAVIS, a citizen of the United States, and a resident of the city of New York, borough of Manhattan, in the county and State of New York, United States of America, have invented a new, original, and ornamental Design for a Dress, of which the following is a specification, reference being had to the accompanying drawing, forming part thereof, wherein the dress is distinguished by the long-waist effect associated with a skirt having an inverted box pleat at the front extending from the bottom to approximately half the height of the

skirt, the upper part of the dress being distinguished by a standing collar associated with a long strip extending from the collar downward an appreciable distance and provided with buttons thereon, a breast pocket, a pair of hip pockets, and a belt at the lower part of the waist section of the dress having depending streamers.

The figure is a perspective view of a dress showing my new design.

What I claim is:

The ornamental design for a dress substantially as shown and described.

TAUBE DAVIS.
